UNITED STATES PATENT OFFICE.

JOHN E. SMITH, OF NEW YORK, N. Y.

DESIGN FOR A CAKE OF SOAP.

SPECIFICATION forming part of Design No. 16,588, dated March 23, 1886.

Application filed December 22, 1885. Serial No. 186,500. Term of patent 14 years.

To all whom it may concern:

Be it known that I, JOHN E. SMITH, a citizen of the United States, residing in the city and county of New York, in the State of New York, have invented and produced a new and original Design for a Cake of Soap, of which the following is a specification, reference being had to the accompanying drawings, forming part thereof.

10 Figure 1 is a view of one of the broad sides or faces of my newly-designed cake of soap. Fig. 2 is a longitudinal section of the same in the plane indicated by the line xx in Fig. 1.

15 The leading feature of my design consists in a prolate ellipsoidal concavity forming an elliptical outline within the contour of the faces of the cake.

20 A A are the broad sides or faces of the cake, in one of which is the prolate ellipsoidal concavity aa , which presents an elliptical outline which comes within the oblong contour c

c of the said face or side, leaving a margin, b , which, as represented in Figs. 2 and 3, is of convex form.

What I claim as my invention is—

25 1. The design for a cake of soap herein shown and described, the same consisting of the cake of soap having the prolate ellipsoidal concavity aa , forming an elliptical outline within the contour cc of one of the faces of the cake.

30 2. The design for a cake of soap herein shown and described, the same consisting of the cake of soap having the prolate ellipsoidal concavity aa and the surrounding convex margin bb within the oblong contour cc of one of the faces of the cake.

JOHN E. SMITH.
